Primary Examiner—Dominic Simone*(74) Attorney, Agent, or Firm*—McDermott, Will & Emery(57) **CLAIM**

The ornamental design for the closure, as shown and described.

DESCRIPTION

FIG. 1 is a perspective view of the closure according to the present invention without a tamper evident band;

FIG. 2 is a plan view of the closure as shown in FIG. 1;

FIG. 3 is a front/rear view of the closure as shown in FIG. 1;

FIG. 4 is a right/left side view of the closure as shown in FIG. 1;

FIG. 5 is an inverted plan view of the closure as shown in FIG. 1;

FIG. 6 is a perspective view of the closure according to the invention with the tamper evident band shown in phantom;

FIG. 7 is a plan view of the closure as shown in FIG. 6;

FIG. 8 is a front/rear view of the closure as shown in FIG. 6;

FIG. 9 is a right/left side view of the closure as shown in FIG. 6; and,

FIG. 10 is an inverted plan view of the closure as shown in FIG. 6.
